UNITED STATES PATENT OFFICE.

ARTHUR G. NEWMAYER, OF NEW ORLEANS, LOUISIANA.

DESIGN FOR AN EMBLEM.

49,829.

Specification for Design.

Patented Oct. 31, 1916.

Application filed September 19, 1916. Serial No. 121,091. Term of patent 14 years.

To all whom it may concern:

Be it known that I, ARTHUR G. NEWMAYER, a citizen of the United States, residing at New Orleans, in the parish of Orleans and State of Louisiana, have invented a new, original, and ornamental Design for an Emblem for a Trade or Other Association, of which the following is a specification, reference being had to the accompanying drawing, forming a part thereof.

The view is an elevation of an emblem showing my new design.

I claim:—

The ornamental design for an emblem, as shown.

ARTHUR G. NEWMAYER.
